ATTORNEY'S

UNITED STATES PATENT OFFICE

ALBERT P. BALL, OF DETROIT, MICHIGAN, ASSIGNOR TO BRIGGS MANUFACTURING COMPANY, OF DETROIT, MICHIGAN, A CORPORATION OF MICHIGAN

CHECK STRAP ASSEMBLY

Application filed January 13, 1930. Serial No. 420,587.

This invention relates generally to door checks, particularly check strap assemblies designed for use in connection with the doors of vehicle bodies, and consists of certain 5 novel features of construction, combinations and arrangements of parts that will be hereinafter more fully described and particularly pointed out in the appended claims.

In the accompanying drawings:

10 Figure 1 is a fragmentary perspective view of a vehicle body with parts broken away and illustrating a check strap embodying my invention;

15 Figure 2 is an enlarged horizontal sectional view through the check strap assembly with the door in closed position;

Figure 3 is a view similar to Figure 2 but showing the door in open position;

20 Figure 4 is an elevation of the construction illustrated in Figure 3;

Figure 5 is a detail elevation of the strap;

Figure 6 is an edge elevation of the strap;

25 Figure 7 is a fragmentary vertical sectional view through a slightly modified construction.

Referring now to the drawings, 1 is a swinging door, and 2 is a supporting pillar therefor of a vehicle body. 3 is a check strap for the door and embodying my invention.

30 As shown, the pillar 2 and door 1 are composite structures, i. e., formed of wood and metal, however, insofar as my strap is concerned these parts may be any suitable construction and design. Preferably the strap

35 3 is formed of spring steel and comprises a single length or strip having enlarged end portions 4 and 5 respectively and an intermediate twisted portion 6. In the present instance the end portion 4 has a pivotal connection with the body pillar 2 and for this

40 purpose has a central circular opening 7 that receives the shank 8 of a suitable bolt in the pillar. As shown, this bolt extends transversely of the metal part 9 of the pillar and

45 is held in place by a suitable nut 10. The head 5 has a slotted connection with the door and is adapted to slide relative thereto. As shown, this head has an elongated slot 11

50 that receives the shank 12 of a bolt extending transversely of the metal part 13 of the

door in a horizontal plane above the bolt shank 8. A suitable nut 14 is used to retain this bolt in position.

Thus with the construction as described, the strap 3 is between and entirely concealed 55 by the pillar 2 and door 1 when the latter is in closed position (see Figures 1 and 2), and the twisted intermediate portion 6 thereof engages opposed faces 16 and 17 respectively of the door and pillar and effectively prevents rattling. When the door 1 is opened, as illustrated in Figures 3 and 4, the upper end 18 of the slot is in engagement with the bolt shank 12 and the door 1 is held against further outward swinging movement. In 60 fact, the intermediate twisted portion 6 is further twisted (see Figure 4) as the door is moved from closed to open position, and as this strap is spring metal and is twisted as just described, the tension thereof is increased 65 as the door moves from closed to open position, hence the door is gradually and increasingly checked as it swings outwardly relative to the pillar.

70 In Figure 7 I have illustrated a slightly modified construction in which the strap 6 is secured to the jamb by means of a screw 20 having a rounded shank portion 21 fitting within a corresponding opening 22 in the strap and having a threaded shank portion 23 engaging a threaded opening 24 in a plate 25 riveted to the metal part 9 of the pillar or jamb. Preferably suitable washers such as 26 and 27 are sleeved upon the shank portion 22 of the screw upon opposite sides of 75 the strap 6. With this method of assembly it is not necessary to apply the check strap until after the vehicle body is trimmed. Ordinarily with check straps now in common use the trim must be removed when it is desired 80 to replace a check strap. Thus the foregoing modification is a definite advance in the art of constructions now in common use.

85 Thus from the foregoing it will be apparent that I have provided an extremely simple 90 check strap assembly in which the strap 3 is normally concealed, and out of the way. Moreover, the assembly is comparatively inexpensive to manufacture and install.

95 What I claim as my invention is:

100

1. In a check strap assembly, a swinging closure, a support therefor, and means for checking the swinging movement of the closure in one direction comprising a strip 5 of metal having end portions connected to the closure and support and having an intermediate twisted portion normally concealed between and engaging opposed faces of the closure and support.
- 10 2. An all-metal check strap for movable closures comprising a single length of spring steel having end portions for attachment respectively to a closure and to a support therefor, and having an intermediate twisted portion 15 for frictional engagement with said closure and support.
- 20 3. An all-metal check strap for movable closures, comprising a substantially flat strip provided at its opposite ends with a circular opening and an elongated slot respectively 25 for receiving attaching means, and having a twisted intermediate portion.
- 30 4. A door construction having in combination, a jamb, a stile hinged thereto, and a flat sheet metal check strap having its ends attached respectively to the jamb and stile for movement in the planes of their meeting faces, said strap lying therebetween in the closed position of the door, said strap adapted upon the separation of the jamb and stile to exercise a restraint upon the door by torsion in the strap induced by an opening of the door.
- 35 5. In a check strap assembly, a support, a door hinged thereto, the support and door having faces in opposed and parallel relation when the door is closed, and a sheet metal check strap lying between said faces when in opposed position, said check strap having 40 its ends respectively connected to the said faces of said support and door and parallel therewith and adapted to be longitudinally twisted intermediate the ends upon separation of said opposed faces when the door is 45 opened, for the purpose set forth.

In testimony whereof I affix my signature.

ALBERT P. BALL.
